DETACHABLE OPERATING HANDLE FOR
RETRACTING BREECH BOLTS

Thomas R. Robinson, Jr., Newtown, Conn., assignor to The Marlin Firearms Company, New Haven, Conn., a corporation of Connecticut

Application August 6, 1947, Serial No. 766,663

26 Claims. (Cl. 42—16)

1

The present invention relates in general to firearms of the type having a reciprocable breech-closing means and more especially to improved operating-means for manually retracting a breech-bolt in the receiver of a firearm.

An object of the invention is to provide a reciprocable breech-bolt with an improved bolt-operating handle in which is combined reliability and strength with ease of assembly, disassembly and low cost of manufacture.

A further object of the invention is to provide improved means for detachably securing a bolt-operating handle to a breech-bolt.

A further object of the invention is to provide an improved detachable operating-handle for retracting a breech-bolt in the receiver of a firearm, the operating-handle being cooperatively associated with the receiver to prevent rotation of the bolt therein.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a side elevation of the receiver of a firearm having a reciprocable breech-bolt adapted to be manually retracted by the improved bolt-operating handle of this invention and including a fragmentary portion of the barrel;

Fig. 2 is a sectional elevation of the side of the receiver and breech-bolt assembly shown in Fig. 1;

Fig. 3 is an end elevation of the receiver on section line 3—3 of Fig. 2;

Fig. 4 is an end elevation of the receiver on section line 4—4 of Fig. 2;

Fig. 5 is an enlarged fragmentary sectional elevation of the receiver and breech-bolt on section line 5—5 of Fig. 3;

Fig. 6 is a fragmentary sectional side elevation of the receiver;

Fig. 7 is a sectional end view of the receiver on line 7—7 of Fig. 6;

Fig. 8 is a side elevation of the breech-bolt showing the operating-handle groove in the forward end thereof and fastening-means extending therein for removably securing the operating-handle in the groove of the breech-bolt;

Fig. 9 is a perspective view of the breech-bolt operating-handle taken from the top side thereof;

2

Fig. 10 is a perspective view of the breech-bolt operating-handle taken from the underside thereof;

Fig. 11 is a side elevation of a modified breech-bolt including a modified operating-handle mounted in the forward end thereof;

Fig. 12 is an enlarged fragmentary sectional side elevation of the receiver of a firearm including the modified breech-bolt and operating-handle shown in Fig. 11;

Fig. 13 is an end elevation on line 13—13 of Fig. 12; and

Fig. 14 is a perspective view of the modified breech-bolt operating-handle.

15 Referring to the drawings which show an exemplary embodiment of the invention, the particular firearm shown is a self-loading repeating type of firearm comprising, in the main, a receiver indicated generally at 15 and a barrel 16 fixedly secured to the forward end thereof. Referring particularly to Fig. 6, the receiver 15 comprises a substantially-cylindrical member preferably formed from a suitable length of tubular steel stock 17. The interior of the cylindrical receiver

20 15 is adapted to provide a breech-bolt chamber 18 of continuous length comprising a rear end-portion of relatively-large diameter and a front end-portion of lesser diameter. To this end, a substantially-cylindrical sleeve or bushing 19 of

30 relatively-thick wall section is inserted in the front end of the receiver and fixedly secured therein by a weld-joint or equivalent fastening-means. In the present embodiment, the internal diameter of the longitudinal bore 20 of the bushing 19, hereinafter referred to as the forward chamber 20 of the receiver 15, is substantially

35 two-thirds the diameter of the rear unbushed portion of a receiver, the latter being hereinafter referred to as the rear chamber 21 of the receiver. The rear end of the receiver is adapted to be closed by a plug 22, which is arranged to make a nice fit in the open rear end thereof and to be fixedly secured therein by a suitable fastening-means

40 23, as indicated in Figs. 1 and 2. The underside or bottom wall of the receiver is provided throughout the rear half of its length with suitable apertures, indicated generally at 24, which communicate with a trigger-plate, indicated generally at 25, in which the fire-control mechanism

45 50 of the firearm is mounted.

The present invention is not concerned with the details of the fire-control mechanism, for any mechanism which is characteristic of a self-loading repeating firearm of the type shown here-

55 in may be used and, hence, the present descrip-

tion is not burdened with a disclosure and detailed description of the fire-control mechanism. The forward chamber 20 of the receiver is adapted to support the rear end of the barrel 16 and to this end, the rear end of the barrel is reduced in diameter to provide a cylindrical wrist 26 arranged to make a snug fit in the open end of the forward chamber 20 with the annular transverse shoulder 27 of the barrel 16 seating firmly against the forward face of the bushing 19. A transverse pin 28 is provided for positively securing the barrel-wrist 26 in the bore of the forward chamber 20. Although a receiver comprising a tubular member having a cylindrical bushing inserted and secured in one end thereof to form a breech-bolt chamber of two diameters is a highly satisfactory and economical construction, it will be appreciated that it is within the purview of the invention to form the receiver, including the forward and rearward chambers 20 and 21 respectively, from a single piece of stock in any well known and approved manner.

Referring to Fig. 1, the right side of the receiver 15 is provided with an ejection-port 29 comprising a substantially-longitudinal slot having elliptical ends 30, each provided with an inwardly-and-downwardly-sloping wall or bevel 31, as shown clearly in Fig. 5. The ejection-port 29 intersects the forward chamber 20 of the receiver substantially intermediate the opposite ends thereof, such that the rearwardly-sloping bevel 31 at the forward end of the port 29 intersects the rear extremity of the barrel-wrist 26, whereby a short portion thereof is exposed, as indicated clearly in Fig. 5. The forwardly-sloping bevel 31 at the rear end of the ejection-port 29 is intersected by the forward end of a longitudinal slot or keyway 32, the longitudinal axis of which is substantially coincident with the longitudinal axis of the ejection-port in a plane intersecting the longitudinal sides thereof, the keyway being substantially rectangular in cross section as indicated clearly in Figs. 4 and 7. Moreover, the keyway 32 extends rearwardly from the beveled rear wall 31 of the ejection-port to the rear end wall or face 33 of the bushing 19, while the bottom of the keyway intersects the inner wall thereof, as shown in Fig. 5. In accordance with this construction, the keyway 32 constitutes a substantially-inverted-U-shaped aperture communicating with both the rear and forward chambers of the receiver and the ejection-port 29, for the purpose hereinafter described.

Mounted to reciprocate longitudinally in the receiver 15 is a breech-bolt, indicated generally at 34 (see Fig. 8), comprising a cylindrical rear end-portion or breech-bolt shank 35 adapted to make a smooth sliding fit in the rear chamber 22 of the receiver; and a forward end-portion or breech-bolt stem 36 which is substantially cylindrical and adapted to make a smooth sliding fit in the forward chamber 20 of the receiver. In the preferred construction, the breech-bolt shank 35 and the breech-bolt stem 36 are formed as two separate elements, the shank being provided with a longitudinal axial aperture 37 in the forward end of which the reduced rear end or neck 38 of the stem 36 is engaged with a press fit. For optimum results, a weld-joint is provided between the mutually-engaging peripheral surfaces of the neck 38 and the longitudinal aperture 37 of the shank to secure the two elements together as an integrated unit. Although the two-piece bolt is quite successful, both from the standpoint

of operation and economy of manufacture, it will be appreciated that the breech-bolt may be turned out of a single piece of stock. The longitudinal axial aperture 37 of the breech-bolt shank 35 is adapted also to accommodate the action-return spring 39 and the striker-member 40 on which the firing-spring 41 is mounted, the forward end of which thrusts against an annular shoulder 42 at the forward end of the striker. 10 The forward end of the action-return spring 39 is shown engaged against an annular shoulder 43 which, in the present embodiment, constitutes the rear end of the neck-portion 38 of the breech-bolt stem 36, while the rear end of the action-return spring 39 is adapted to seat against a suitable shoulder (not shown) in the end plug 22 of the receiver.

The neck-portion 38 of the breech-bolt stem 36 is provided with a longitudinal axial aperture 46 which constitutes a counterbore of the firing-pin aperture 47. The latter extends through the breech-bolt stem 36 from its counterbore 46 forwardly and in an upwardly-inclined direction, as indicated in Figs. 3 and 5, to the face of the bolt, 20 25 the forward end of the firing-pin aperture being reduced in diameter as at 48 to slidably support the needle 49 of the firing-pin 50. The latter is dimensioned to make a sliding fit in the longitudinal aperture 47 and forms an annular shoulder 51 with its needle 49 against which the rear end 30 35 of a firing-pin retracting-spring 52 is engaged, the forward end of the spring 52 abutting the annular shoulder 53 formed at the rear end of the needle-supporting aperture 48. The rear end 35 of the firing-pin 50 is provided with an enlarged head 54 which is accommodated in the counterbore 46 of the breech-bolt stem and is adapted to be struck by the nose-portion 55 of the striker-member when the latter is released, as indicated 40 in Fig. 5. The underside of the breech-bolt stem 36 is provided with a pair of longitudinally-spaced parallel slots 56, as indicated in Figs. 3 and 4, which constitute relief-recesses for the cartridge guide-means for automatically feeding cartridges to the breech-end of the barrel.

Referring particularly to Figs. 5 and 8, in the present embodiment the forward end of the breech-bolt stem 36 is encircled by a shallow groove 57 which is adapted to accommodate a circular split band 58. The latter constitutes the anchoring-means of an extractor-claw 59 which is formed integrally with and substantially at right angles to a forwardly-extending reach 60 of the anchoring-band 58. As indicated in Fig. 2, the extractor-claw 59 is adapted to be accommodated in a suitable notch 61 in the exposed portion of the stem 26 of the barrel when the breech-bolt is in breech-closing position.

When the breech-bolt is in its forward breech-closing position, it is sometimes both necessary and desirable to manually retract the breech-bolt. Referring especially to Figs. 5, 9 and 10, the manually-operated breech-bolt actuating-means or operating-handle of this invention is indicated generally at 62 and comprises a relatively-long narrow blade-like member substantially equal in width to the width of the longitudinal keyway 32 in the receiver, so as to make sliding engagement therein for the purpose hereinafter described. The forward end or reach 63 of the operating-handle is provided with a finger-grip 64 bent up therefrom and extending outwardly laterally and rearwardly at an angle of from 10 to 15 degrees, the outer extremity of the finger-grip

64 being suitably shaped to facilitate gripping. The rear end-portion of the breech-bolt operating-handle constitutes an integral elongated protuberance or tenon 65 which projects downwardly below the plane of the underside of the reach 63 and forms a substantially-transverse shoulder or abutment 66 therewith. The tenon 65 is substantially U-shaped in cross section and its bottom is provided with an upset knee 67 which is formed integrally therein and projects upwardly therefrom adjacent the forward end of the tenon.

The operating-handle 62 is adapted to be mounted on the breech-bolt stem 36 and to this end the latter is provided throughout its length with a longitudinal retaining-groove 68 in its periphery, the forward end of the groove being relatively shallow as at 680 to receive the reach 63 of the operating-handle, and the rear end-portion of the retaining-groove being relatively deep so as to form, in effect, a socket or mortise 69 to accommodate the tenon 65 of the operating-handle, the shoulder 66 of the tenon being adapted to abut the substantially-transverse front end wall or abutment 70 of the mortise 69. When assembled in the retaining-groove 68 of the breech-bolt stem 36, the rear end of the tenon 65 is adapted to abut the rear end wall or abutment 71 of the mortise which, in the present embodiment, constitutes the forward end of the shank 35 of the breech-bolt. Thus, the operating-handle is securely held against relative longitudinal movement on the stem 36 of the reciprocable breech-bolt. The breech-bolt is adapted to be assembled in the receiver by inserting the breech-bolt, stem-end first, into the open rear end of the receiver, the longitudinal retaining-groove 68 of the stem being located on the stem in a position such that when the breech-bolt is fully assembled in the receiver, the groove 68 will be substantially opposite the ejection-port 29 of the receiver and parallel to and immediately opposite the keyway 32 thereof, as shown clearly in Figs. 1 and 4. In the present embodiment, a plane through the longitudinal axis of the groove 68 and perpendicular to the bottom thereof (see Figs. 3 and 4), makes an angle of substantially 27° with a horizontal plane through the longitudinal axis of the breech-bolt. Thus, the operating-handle 62 is located substantially opposite the ejection-port 29 of the receiver so that its finger-grip 64 will project laterally therethrough and its tenon 65 will slidably engage in the keyway 32 of the receiver, as indicated clearly in Fig. 5.

Cooperatively associated with the breech-bolt operating-means is fastening-means arranged to detachably secure the former to the breech-bolt. In the present embodiment, the fastening-means comprises a substantially-cylindrical pin 72 which may be solid or tubular in construction, and which is of a resilient nature such that it may be flexed. The pin 72 is adapted to be fixedly secured at its rear end in a longitudinal aperture or socket 73 which is formed in the forward end 71 of the breech-bolt shank 35 substantially parallel to the longitudinal axis thereof, the longitudinal axis of the pin-aperture 73 being substantially in axial alignment with the keyway 32 of the receiver. The portion of the pin 72 which is forwardly of its rear end is hereinafter referred to as its "reach" and is adapted to extend forwardly through the keyway 32 into the longitudinal channel of the tenon 65 of the operating-handle 62. The length of the reach of the pin 72 is such that its forward end is adapted to engage against the upset knee 67 in the bottom of the tenon 65 and to be flexed

outwardly laterally thereby so as to exert an inwardly-directed force on the tenon of the operating-handle so as to hold the tenon in the mortise of the breech-bolt.

5 The rear end of the pin 72 is normally held in the longitudinal aperture 73 by a drive-fit or equivalent fastening-means. In order to provide for the removal of the pin 72, in the event of its breakage, a radial groove 74 is milled or otherwise formed in the breech-bolt shank 35 adjacent the forward end thereof, the longitudinal axis of the groove 74 being parallel to and in the plane of the longitudinal axis of the aperture 73, and the depth of the groove being such that its bottom intersects the rear end of the longitudinal aperture 73. Consequently, a wedge or similar tool may be inserted into the radial groove against the rear end of the pin 72 for driving the latter forwardly out of its aperture 73.

10 20 Although the pin 72 is shown as a separate element of the operating-handle, it is within the purview of this invention to form the pin or its equivalent as an integral part thereof.

It is understood that normally the breech-bolt 25 will be operated automatically. However, it may be reciprocated manually. Thus, in order to manually retract the breech-bolt, the marksman grasps the finger-grip 64 of the operating-handle and pulls rearwardly thereon. Since the tenon 30 65 of the latter is fixedly secured against longitudinal movement in the mortise of the breech-bolt, a rearward pull upon the finger-grip will simultaneously move the operating-handle and breech-bolt in a rearward direction so as to retire the breech-bolt to its rearmost position in the receiver. The breech-bolt may be advanced manually from its retired position in the receiver by thrusting forwardly on the finger-grip 64 of the operating-handle, the forward thrust on the latter being transmitted to the breech-bolt by engagement of the shoulder 66 of the operating-handle with the front end wall 70 of the mortise 69. It should be pointed out, also, that mutual engagement of the shoulder 66 of the tenon and the wall 70 of the mortise prevents the operating-handle from being thrown forwardly out of the breech-bolt as the latter slams forward into breech-closing position. Moreover, since the tenon 65 of the operating-handle makes longitudinal sliding engagement in the keyway 32 of the receiver and is precluded from transverse movement with respect to the breech-bolt by engagement of the sides of the tenon 65 with the corresponding laterally-spaced walls of the mortise 69 thereof, the operating-handle thereby effectively locks the breech-bolt against rotation in the receiver.

55 The removal of the operating-handle from the breech-bolt may be readily accomplished by 60 grasping the finger-grip 64 thereof and pulling it outwardly laterally so as to lift the shoulder 66 of its tenon up over the front end wall 70 of the mortise against the resistance of the resilient pin 72. Thereupon, the operating-handle may be 65 pushed forwardly relative to the breech-bolt out of its retaining-slot 68. The breech-bolt operating-handle may be assembled on the breech-bolt in the reverse order, that is to say, by inserting the rear end of the operating-handle beneath the forward free end of the pin 72 and pushing rearwardly on the finger-grip 64 until the rear end of the operating-handle and, in particular, its tenon 65 abut against the front wall 71 of the breech-bolt shank 35 and the shoulder 66 of the tenon drops down behind the front end

wall 70 of the mortise, thereby locking the operating-handle against longitudinal movement relative to the breech-bolt. The lateral force of the flexed reach of the pin 72 then acts against the upset knee of the tenon to hold the latter firmly in the mortise of the breech-bolt.

A modification of the invention is shown in Figs. 11 through 14. In its modified form the breech-bolt operating-handle comprises an elongated rod-like member 75 substantially rectangular in cross section and provided on its underside intermediate its opposite ends 76 and 77 respectively with a cut-out 78, whereby the portion of the rod intermediate its opposite ends is rendered less stiff and more flexible in character. The rear end-portion 76 of the operating-handle is provided with a socket-fitting element or stem 79 which is substantially round in cross section and adapted to make a snug sliding fit in a longitudinal aperture, hereinafter described, in the forward end of the breech-bolt shank, as shown in Figs. 11 and 12. The forward end portion 77 of the operating-handle is provided with an integral protuberance 80 which sets back a relatively short distance from the forward extremity of the operating-handle and constitutes a substantially cylindrical lug projecting downwardly from the underside of the handle substantially perpendicular thereto.

Formed integrally or otherwise secured at the forward extremity of the operating-handle and on the topside thereof is a finger-grip 81 which, in the present embodiment, constitutes a substantially-flat disk-shaped member preferably provided with knurling or transverse grooves to afford a good grip.

The operating-handle 75 is adapted to be detachably secured to a breech-bolt 82 (see Figs. 11, 12 and 13) which is substantially identical to the breech-bolt 34 shown and described above, except that the longitudinal groove or mortise 69 is dispensed with and an equivalent aperture 83 is provided in the forward end of the breech-bolt 82, the aperture 83 being formed radially thereof and forwardly of the split band 58 of the extractor-claw. A longitudinal aperture or socket 84 is provided in the forward end of the shank-portion of the breech-bolt substantially identical in configuration and function to the aperture 73 of the previously-described breech-bolt 34.

To assemble the operating-handle 75 in the breech-bolt 82, the socket-fitting stem 79 of the handle is thrust rearwardly into the longitudinal aperture 84 until the lug 80 of the handle is substantially opposite the radial aperture 83 in the forward end of the breech-bolt. During this interval, the bolt-operating handle is flexed outwardly about its stem 79 as a fulcrum, due to engagement of the lug 80 at the forward end of the handle with the periphery of the breech-bolt. However, as soon as the lug 80 arrives opposite the radial aperture 83, the resiliency of the flexed handle and, in particular, the portion of reduced cross section hereinafter referred to as the "reach," acting in conjunction with the socketed stem 79, urges the lug into the aperture where it is held against accidental displacement by the inherent resilient force of the reach. When assembled in the breech-bolt, the right- and left-hand walls of the radial aperture 83 constitute laterally-spaced abutments respectively adapted to be engaged by the corresponding sides of the lug 80 of the operating-handle to prevent movement of the latter transversely with respect to the breech-bolt. Further, the

front and rear walls of the radial aperture 83 constitute rearwardly- and forwardly-facing abutments respectively adapted to be engaged by the corresponding sides of the lug, which are held in juxtaposition thereto by the resilient reach of the handle, to prevent the operating-handle from being displaced longitudinally with respect to the breech-bolt; while engagement of the socket-fitting stem 79 of the operating-handle in the socket 84 of the breech-bolt retains the operating-handle in longitudinal alignment therewith, such that engagement of the operating-handle in the keyway 32 in the rear wall of the ejection-port effectively locks the breech-bolt from rotating in the chamber of the receiver.

The operating-handle may be readily removed from the breech-bolt, if desired, by grasping the finger-grip 81 and pulling outwardly thereon so as to flex the handle and draw its lug 80 out of the radial aperture 83, whereupon a forward thrust on the operating-handle will withdraw its socket-fitting stem 79 from the longitudinal aperture of the breech-bolt.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In a firearm, including in combination: a receiver having a breech-bolt chamber; a breech-bolt reciprocably mounted in said chamber, said breech-bolt having a longitudinal socket open in one direction; a transverse abutment remote from the open end of said longitudinal socket and facing in a direction opposite thereto; and a breech-bolt operating-handle having a resilient-element fitted in said socket and an integral abutment remote from the socket-fitting resilient-element, said resilient socket-fitting element being arranged to bear inwardly to hold the integral abutment of said bolt-operating means resiliently in juxtaposition to the transverse abutment of said breech-bolt.

2. In a firearm, including in combination: a receiver having a breech-bolt chamber; a breech-bolt reciprocably mounted in said chamber, said breech-bolt having a longitudinal socket open in one direction; a transverse abutment remote from the open end of said longitudinal socket and facing in a direction opposite thereto; and a breech-bolt operating-handle having an elongated resilient-element fitted in said socket, and an integral abutment remote from the socket-fitting resilient-element, said resilient socket-fitting element being arranged to bear inwardly to hold the integral abutment of said bolt-operating member resiliently in juxtaposition to the transverse abutment of said breech-bolt.

3. In a firearm, including in combination: a receiver having a breech-bolt chamber; a breech-bolt reciprocably mounted in said chamber, said breech-bolt having a longitudinal socket open in one direction and a transverse abutment remote from the open end of said longitudinal socket and facing in a direction opposite thereto and a second transverse abutment opposite said first abutment; and a breech-bolt operating-handle having a resilient-element fitted in said socket and an integral protuberance remote from the resilient socket-fitting element and substantially

intermediate the first and second transverse abutments of said breech-bolt, said resilient socket-fitting element being arranged to bear inwardly to hold the integral protuberance of said bolt-operating means resiliently in juxtaposition to the first and second transverse abutments of said breech-bolt.

4. In a firearm, including in combination: a receiver having a breech-bolt chamber; a breech-bolt reciprocably mounted in said chamber, said breech-bolt having a longitudinal socket open in one direction; a transverse abutment remote from the open end of said longitudinal socket and facing in a direction opposite thereto; a pair of laterally-spaced abutments; and a breech-bolt operating-handle having an element fitted in said socket and provided with a resilient reach, and an integral abutment remote from the socket-fitting element and arranged to engage between the pair of laterally-spaced abutments of said breech-bolt, said socket-fitting element and reach being arranged to coact so as to hold the integral abutment of said bolt-operating means resiliently in juxtaposition to the transverse abutment of said breech-bolt.

5. In a firearm, including in combination: a receiver having a breech-bolt chamber; a breech-bolt reciprocably mounted in said chamber, said breech-bolt having a longitudinal socket open in one direction; a transverse abutment remote from the open end of said longitudinal socket and facing in a direction opposite thereto; a second transverse abutment opposite said first abutment and a pair of laterally-spaced abutments; and a breech-bolt operating-handle having an element fitted in said socket and provided with a resilient reach, and an integral protuberance remote from the socket-fitting element, said integral protuberance being arranged to extend between the pair of laterally-spaced abutments and substantially intermediate the first and second transverse abutments of said breech-bolt, said socket-fitting element and reach being arranged to coact so as to hold the integral protuberance of said bolt-operating means resiliently in juxtaposition to the first and second transverse abutments of said breech-bolt.

6. In a firearm, including in combination: a receiver having a breech-bolt chamber; an ejection-port intersecting the forward end of said chamber and a longitudinal keyway on the inside wall of said chamber intersecting the rear wall of said ejection-port; a breech-bolt reciprocably mounted in said chamber, said breech-bolt having a longitudinal socket open in one direction and a transverse abutment removed from the open end of said longitudinal socket and facing in a direction opposite thereto; and a breech-bolt operating-handle arranged to slidily engage in the longitudinal keyway of said receiver to prevent rotation of said breech-bolt in the chamber thereof, said breech-bolt operating-handle having an element fitted in said socket and provided with a resilient reach, and an integral abutment remote from the socket-fitting element, said socket-fitting element and reach being arranged to coact so as to hold the integral abutment of said bolt-operating handle resiliently in juxtaposition to the transverse abutment of said breech-bolt.

7. In a firearm, including in combination: a receiver having a breech-bolt chamber; a breech-bolt reciprocably mounted in said chamber, said breech-bolt having a socket adjacent its front end; a breech-bolt operating-handle; means to connect said breech-bolt operating-handle to said

breech-bolt comprising an integral protuberance of said operating-handle arranged to seat in said socket whereby a force exerted on said handle moves said breech-bolt longitudinally in said chamber; and fastening-means constructed and arranged to detachably secure said breech-bolt operating-handle to said breech-bolt, said fastening-means comprising a resilient-element of said operating-handle arranged to hold said integral protuberance resiliently in said socket.

8. In a firearm, including in combination: a receiver having a breech-bolt chamber; a breech-bolt reciprocably mounted in said chamber, said breech-bolt having a socket adjacent its front end; a breech-bolt operating-handle, means to connect said breech-bolt operating-handle to said breech-bolt comprising an integral protuberance of said operating-handle arranged to seat in said socket whereby a force exerted on said handle moves said breech-bolt longitudinally in said chamber; and fastening-means constructed and arranged to detachably secure said breech-bolt operating-handle to said breech-bolt, said fastening-means comprising a resilient-element of said operating-handle secured at one end to said breech-bolt and arranged to exert a force transversely of said breech-bolt operating-handle to hold said integral protuberance resiliently in said socket.

9. In a firearm, including in combination: a receiver having a breech-bolt chamber; a breech-bolt reciprocably mounted in said chamber, said breech-bolt having a mortise adjacent its front end; a breech-bolt operating-handle; means to connect said breech-bolt operating-handle to said breech-bolt comprising a tenon of said operating-handle arranged to seat in said mortise, whereby a rearward pull on said handle retracts said breech-bolt in said chamber; and fastening-means constructed and arranged to detachably secure said breech-bolt operating-handle to said breech-bolt, said fastening-means comprising a resilient-member arranged to hold said tenon in said mortise.

10. In a firearm, including in combination: a receiver having a breech-bolt chamber; a breech-bolt reciprocably mounted in said chamber, said breech-bolt having a mortise adjacent its front end; a breech-bolt operating-handle; means to connect said breech-bolt operating-handle to said breech-bolt comprising a tenon of said operating-handle arranged to seat in said mortise, whereby a rearward pull on said handle retracts said breech-bolt in said chamber; and fastening-means constructed and arranged to detachably secure said breech-bolt operating-handle to said breech-bolt, said fastening-means comprising a resilient-member secured at one end to said breech-bolt and arranged to engage at its opposite free end against said breech-bolt operating-handle to hold said tenon in said mortise.

11. In a firearm, including in combination: a receiver having a breech-bolt chamber; a breech-bolt reciprocably mounted in said chamber, said breech-bolt having a mortise adjacent its front end; a breech-bolt operating-handle; means to connect said breech-bolt operating-handle to said breech-bolt comprising a tenon of said operating-handle arranged to seat in said mortise, whereby a rearward pull on said handle retracts said breech-bolt in said chamber; and fastening-means constructed and arranged to detachably secure said breech-bolt operating-handle to said breech-bolt, said fastening-means comprising a

flexible member arranged to hold said tenon in said mortise.

12. In a firearm, including in combination: a receiver having a breech-bolt chamber; a breech-bolt reciprocably mounted in said chamber, said breech-bolt having a mortise adjacent its front end; a breech-bolt operating-handle; means to connect said breech-bolt operating-handle to said breech-bolt comprising a tenon of said operating-handle arranged to seat in said mortise, whereby a rearward pull on said handle retracts said breech-bolt in said chamber; and fastening-means constructed and arranged to detachably secure said breech-bolt operating-handle to said breech-bolt, said fastening-means comprising a flexible member fixedly secured at one end to said breech-bolt and arranged to engage at its opposite free end against said tenon to hold said tenon in said mortise.

13. In a firearm, including in combination: a receiver having a breech-bolt chamber; a breech-bolt reciprocably mounted in said chamber, said breech-bolt having a mortise adjacent its front end; a breech-bolt operating-handle; means to connect said breech-bolt operating-handle to said breech-bolt comprising a tenon of said operating-handle having an upset knee and arranged to seat in said mortise, whereby a rearward pull on said handle retracts said breech-bolt in said chamber; and fastening-means constructed and arranged to detachably secure said breech-bolt operating-handle to said breech-bolt, said fastening-means comprising a flexible member fixedly secured at one end to said breech-bolt and arranged to engage at its opposite free end against the said upset knee of said tenon to hold said tenon in said mortise.

14. In a firearm, including in combination: a receiver having a breech-bolt chamber; a breech-bolt reciprocably mounted in said chamber, said breech-bolt having a mortise adjacent its front end; a breech-bolt operating-handle; means to connect said breech-bolt operating-handle to said breech-bolt comprising a tenon of said operating-handle provided with a longitudinal groove and arranged to seat in said mortise, whereby a rearward pull on said handle retracts said breech-bolt in said chamber; and fastening-means constructed and arranged to detachably secure said breech-bolt operating-handle to said breech-bolt, said fastening-means comprising a flexible member fixedly secured at one end to said breech-bolt and arranged to extend into the longitudinal groove of said tenon and to engage at its opposite free end against said tenon thereby to hold said tenon in said mortise.

15. In a firearm, including in combination: a receiver having a breech-bolt chamber; a breech-bolt reciprocably mounted in said chamber, said breech-bolt having a mortise adjacent its front end; a breech-bolt operating-handle; means to connect said breech-bolt operating-handle to said breech-bolt comprising a tenon of said operating-handle provided with a longitudinal groove having an upset knee in the bottom thereof; said tenon being arranged to seat in said mortise, whereby a rearward pull on said handle retracts said breech-bolt in said chamber; and fastening-means constructed and arranged to detachably secure said breech-bolt operating-handle to said breech-bolt, said fastening-means comprising a flexible member fixedly secured at one end to said breech-bolt and arranged to extend into the longitudinal groove of said tenon and to engage its opposite free end against the said upset knee

thereof so as to hold said tenon in said mortise.

16. In a firearm, including in combination: a receiver having a breech-bolt chamber, an ejection-port intersecting the forward end of said chamber and a longitudinal keyway on the inside wall of said chamber intersecting the rear wall of said ejection-port; a breech-bolt reciprocably mounted in said chamber, said breech-bolt having a mortise adjacent its front end substantially opposite said ejection-port; a breech-bolt operating-handle; means to connect said breech-bolt operating-handle to said breech-bolt comprising a tenon of said operating-handle arranged to seat in said mortise and to slidably engage in the longitudinal keyway of said receiver to prevent rotation of said breech-bolt in the chamber thereof, said breech-bolt operating-handle also having a finger-grip projecting laterally therefrom through the said ejection-port, whereby a rearward pull on said finger-grip retracts said breech-bolt in said chamber; and fastening-means constructed and arranged to detachably secure said breech-bolt operating-handle to said breech-bolt, said fastening-means comprising a flexible member fixedly secured at one end to said breech-bolt in axial alignment with the said keyway of said receiver and arranged to engage its opposite free end against said breech-bolt operating-handle to hold said tenon in said mortise.

17. In a firearm, including in combination: a receiver having a breech-bolt chamber, an ejection-port intersecting the forward end of said chamber and a longitudinal keyway on the inside wall of said chamber intersecting the rear wall of said ejection-port; a breech-bolt reciprocably mounted in said chamber, said breech-bolt having a mortise adjacent its front end substantially opposite said ejection-port; a breech-bolt operating-handle; means to connect said breech-bolt operating-handle to said breech-bolt comprising a tenon of said operating-handle arranged to seat in said mortise and to slidably engage in the longitudinal keyway of said receiver to prevent rotation of said breech-bolt in the chamber thereof, said breech-bolt operating-handle also having a finger-grip projecting laterally therefrom through the said ejection-port, whereby a rearward pull on said finger-grip retracts said breech-bolt in said chamber; and fastening-means constructed and arranged to detachably secure said breech-bolt operating-handle to said breech-bolt, said fastening-means comprising a flexible member fixedly secured at one end to said breech-bolt in axial alignment with the said keyway of said receiver, the opposite end of said flexible member being arranged to extend through said keyway and to engage its free end against said breech-bolt operating-handle to hold said tenon in said mortise.

18. In a firearm including in combination: a receiver having a breech-bolt chamber, an ejection-port intersecting the forward end of said chamber and a longitudinal keyway on the inside wall of said chamber intersecting the rear wall of said ejection-port; a breech-bolt reciprocably mounted in said chamber, said breech-bolt having a mortise adjacent its front end substantially opposite said ejection-port; a breech-bolt operating-handle; means to connect said breech-bolt operating-handle to said breech-bolt comprising a channeled tenon of said operating-handle arranged to seat in said mortise and to slidably engage in the longitudinal keyway of said receiver to prevent rotation of said breech-bolt in the

chamber thereof, said breech-bolt operating-handle also having a finger-grip projecting laterally therefrom through the said ejection-port, whereby a rearward pull on said finger-grip retracts said breech-bolt in said chamber; and fastening-means constructed and arranged to detachably secure said breech-bolt operating-handle to said breech-bolt, said fastening-means comprising a flexible member fixedly secured at one end to said breech-bolt in axial alignment with the said keyway of said receiver and arranged to extend forwardly through said keyway and into the channel of said tenon thereby to engage its opposite free end against said breech-bolt operating-handle to hold said channeled tenon in said mortise.

19. In a firearm including in combination: a receiver having a breech-bolt chamber, an ejection-port intersecting the forward end of said chamber and a longitudinal keyway on the inside wall of said chamber intersecting the rear wall of said ejection-port; a breech-bolt reciprocably mounted in said chamber, said breech-bolt having a mortise adjacent its front end substantially opposite said ejection-port; a breech-bolt operating-handle; means to connect said breech-bolt operating-handle to said breech-bolt comprising a channeled tenon of said operating-handle having an upset knee in the bottom thereof, said channeled tenon being arranged to seat in said mortise and to slidily engage in the longitudinal keyway of said receiver to prevent rotation of said breech-bolt in the chamber thereof, said breech-bolt operating-handle also having a finger-grip projecting laterally therefrom through the said ejection-port, whereby a rearward pull on said finger-grip retracts said breech-bolt in said chamber; and fastening-means constructed and arranged to detachably secure said breech-bolt operating-handle to said breech-bolt, said fastening means comprising a flexible member fixedly secured at one end to said breech-bolt in axial alignment with the said keyway of said receiver and arranged to extend forwardly through said keyway and into the channel of said tenon thereby to engage its opposite free end against the upset knee thereof to hold said channeled tenon in said mortise.

20. In a firearm including in combination: a receiver having a breech-bolt chamber, an ejection-port intersecting the forward end of said chamber and a longitudinal keyway on the inside wall of said chamber intersecting the rear wall of said ejection-port; a breech-bolt reciprocably mounted in said chamber, said breech-bolt having a mortise adjacent its front end substantially opposite the said ejection-port; a breech-bolt operating-handle; means to connect said breech-bolt operating-handle to said breech-bolt comprising a tenon of said operating-handle arranged to seat in said mortise and to slidily engage in the longitudinal keyway of said receiver to prevent rotation of said breech-bolt in the chamber thereof, said breech-bolt operating-handle also having a finger-grip projecting laterally therefrom through the said ejection-port whereby a rearward pull on said finger-grip retracts said breech-bolt in said chamber; fastening-means comprising a flexible member constructed and arranged to detachably secure said breech-bolt operating-handle to said breech-bolt; and means to fixedly secure one end of said flexible member to said breech-bolt in axial alignment with the said keyway of said receiver, the opposite free end of said flexible member being adapted thereby to extend through said keyway and to engage against said breech-

bolt operating-handle to hold said tenon in said mortise.

21. In a firearm including in combination: a receiver having a breech-bolt chamber, an ejection-port intersecting the forward end of said chamber and a longitudinal keyway on the inside wall of said chamber intersecting the rear wall of said ejection-port; a breech-bolt reciprocably mounted in said chamber, said breech-bolt having a mortise adjacent its front end substantially opposite said ejection-port; a breech-bolt operating-handle; means to connect said breech-bolt operating-handle to said breech-bolt comprising a channeled tenon of said operating-handle having an upset knee in the bottom thereof, said channeled tenon being arranged to seat in said mortise and to slidily engage in the longitudinal keyway of said receiver to prevent rotation of said breech-bolt in the chamber thereof, said breech-bolt operating-handle also having a finger-grip projecting laterally therefrom through the said ejection-port, whereby a rearward pull on said finger-grip retracts said breech-bolt in said chamber; fastening-means comprising a flexible member constructed and arranged to detachably secure said breech-bolt operating-handle to said breech-bolt; means to fixedly secure one end of said flexible member to said breech-bolt in axial alignment with the said keyway of said receiver, the opposite free end of said flexible member being adapted thereby to extend forwardly through said keyway and into the channel of said tenon and to engage against the upset knee thereof so as to hold said channeled tenon in said mortise; and an aperture in said breech-bolt to provide access to the fixed end of said flexible member for removing the latter from said breech-bolt.

22. In a firearm including in combination: a receiver having a breech-bolt chamber comprising a rear end-portion and an axially-aligned front end-portion which is reduced in diameter and forms a transverse shoulder therewith, an ejection-port intersecting the front end-portion of said chamber and a longitudinal keyway on the inside wall of said transverse shoulder joining the rear end-portion of said chamber to said ejection-port; a breech-bolt reciprocably mounted in said chamber, said breech-bolt comprising a shank-portion supported in the rear end-portion of said chamber and a stem-portion of reduced diameter supported in the reduced front end of said chamber, the said stem-portion of said breech-bolt having a longitudinal mortise therein substantially opposite said ejection-port; a breech-bolt operating-handle; means to connect said breech-bolt operating-handle to the stem-portion of said breech-bolt comprising a channeled tenon of said operating-handle having an upset knee in the bottom thereof, said channeled tenon being arranged to seat snugly in said mortise and to slidily engage in the longitudinal keyway of said receiver to prevent rotation of said breech-bolt in the chamber thereof, said breech-bolt operating-handle also having a finger-grip projecting laterally therefrom through the said ejection-port whereby a rearward pull on said finger-grip retracts said breech-bolt in said chamber; and fastening-means constructed and arranged to detachably secure said breech-bolt operating-handle to the stem-portion of said breech-bolt, said fastening-means comprising a relatively-stiff flexible member, one end of which is arranged to be fixedly secured in a longitudinal aperture in the shank-portion of said breech-bolt in axial alignment with the said keyway, the opposite free

end of said flexible member being adapted thereby to extend forwardly through said keyway and into the channel of said tenon and to engage against the upset knee thereof so as to hold said tenon in said mortise.

23. In a firearm, including in combination: a receiver having a breech-bolt chamber comprising a rear end-portion and an axially-aligned front end-portion which is reduced in diameter and forms a transverse shoulder therewith, an ejection-port intersecting the front end-portion of said chamber and a longitudinal keyway on the inside wall of said transverse shoulder joining the rear end-portion of said chamber to said ejection-port; a breech-bolt reciprocably mounted in said chamber, said breech-bolt comprising a shank-portion supported in the rear end-portion of said chamber and a stem-portion of reduced diameter supported in the reduced front end of said chamber, the said stem-portion of said breech-bolt having a longitudinal mortise therein substantially opposite said ejection-port; a breech-bolt operating-handle; means to connect said breech-bolt operating-handle to the stem-portion of said breech-bolt comprising a channeled tenon of said operating-handle having an upset knee in the bottom thereof, said channeled tenon being arranged to seat snugly in said mortise and to slidily engage in the longitudinal keyway of said receiver to prevent rotation of said breech-bolt in the chamber thereof, said breech-bolt operating-handle also having a finger-grip projecting laterally therefrom through the said ejection-port whereby a rearward pull on said finger-grip retracts said breech-bolt in said chamber; fastening-means constructed and arranged to detachably secure said breech-bolt operating-handle to the stem-portion of said breech-bolt, said fastening-means comprising a relatively-stiff flexible member, one end of which is arranged to be fixedly secured in a longitudinal aperture in the shank-portion of said breech-bolt in axial alignment with the said keyway, the opposite free end of said flexible member being adapted thereby to extend forwardly through said keyway and into the channel of said tenon and to engage against the upset knee thereof so as to hold said tenon in said mortise; and a transverse aperture in the shank-portion of said breech-bolt intersecting the rear end of the flexible-member receiving-aperture thereof to provide access to the rear end of said flexible member for removing the latter from said breech-bolt.

24. In a firearm, including in combination: a receiver having a breech-bolt chamber; a breech-bolt reciprocably mounted in said chamber, said

breech-bolt having a longitudinal socket open in one direction and a radial socket remote from the open end of said longitudinal socket; and a breech-bolt operating-handle having a rearwardly-extending stem engaged in the longitudinal socket of said breech-bolt and provided with a resilient reach, and an integral lug remote from said stem and substantially opposite the radial socket of said breech-bolt, said stem and reach being arranged to coact so as to exert a force transversely of said breech-bolt operating-handle to hold said integral lug resiliently in said radial socket.

25. In a firearm, including in combination: a receiver having a breech-bolt chamber; a breech-bolt reciprocably mounted in said chamber, said breech-bolt having a longitudinal socket open in one direction and a radial socket remote from the open end of said longitudinal socket; and a breech-bolt operating-handle comprising an elongated member having a rearwardly-extending stem engaged in the longitudinal socket of said breech-bolt and provided with a resilient reach, and an integral lug remote from said stem and substantially opposite the radial socket of said breech-bolt, said stem and reach being arranged to coact so as to exert a force transversely of said breech-bolt operating-handle to hold said integral lug resiliently in said radial socket.

26. In a firearm, including in combination: a receiver having a breech-bolt chamber; an ejection-port intersecting the forward end of said chamber and a longitudinal keyway on the inside wall of said chamber intersecting the rear wall of said ejection-port; a breech-bolt reciprocably mounted in said chamber, said breech-bolt having a longitudinal socket open in one direction and a radial socket remote from the open end of said longitudinal socket; and a breech-bolt operating-handle comprising an elongated member arranged to slidily engage in the longitudinal keyway of said receiver to prevent rotation of said breech-bolt in the chamber thereof, said breech-bolt operating-handle having a rearwardly-extending stem engaged in the longitudinal socket of said breech-bolt and provided with a resilient reach, an integral lug remote from said stem and substantially opposite the radial socket of said breech-bolt, said stem and reach being arranged to coact so as to exert a force transversely of said breech-bolt operating-handle to hold said integral lug resiliently in said radial socket, and a finger-grip projecting laterally from said elongated member.
